UNITED STATES PATENT OFFICE.

BYERS W. KADEL, OF BALTIMORE, MARYLAND.

RAILWAY CAR.

Application filed December 17, 1924. Serial No. 756,506.

My invention relates to the construction of railway cars and particularly to the mechanism by which swinging doors for discharging lading are maintained in closed position. 5 A principal object of the invention is to provide an improved form of door stiffener which is related to the door and to the door latching mechanism in a very efficient manner. Another object of the invention is 10 to provide a pivoted latch for maintaining the door in closed position which is adapted to react upon the door stiffener so as to resist bulging of the door. More specific objects are concerned with the relation of the door 15 stiffener member to the door and to the door supporting latch and to the locking member by which said latch is normally maintained in locked position.

A principal feature of the invention consists in mounting a stiffening member upon 20 the outer face of the hinged door of a railway car, the said stiffening member being formed with a channel which faces towards the door, a door supporting latch which extends outwardly beyond the end of the stiffening member being pivotally mounted within 25 the channel of the latter, and means carried by the car body being provided to constitute a ledge or shoulder adjacent the stiffening member adapted to cooperate with 30 the latch to hold the door shut.

A further feature of the invention consists in mounting upon the outer face of the car door a stiffening member of channel 35 form which comprises spaced main flanges, marginal flanges at the free edges of the main flanges, and a web uniting the main flanges, the said marginal flanges being disposed between the said web and the door, means extending through 40 said marginal flanges being provided for securing the stiffening member to the door, a shouldered member being mounted on the car body adjacent the end of the 45 stiffening member, and a pivoted latch being arranged between the main flanges of the stiffening member and extending beyond the latter so as to engage the shouldered member for the purpose of holding the door shut.

50 A still further feature of the invention consists in mounting upon the outer face of a car door a stiffening member having spaced flanges and a web connecting the latter, the flanges being disposed substantially normal to the plane of the door and

the said web being spaced from the latter, a door securing latch being pivoted with respect to said stiffening member between the flanges thereof, means carried by the car body being provided to serve as a ledge 60 or shoulder which is adapted to be engaged by said latch to hold the door shut, and a locking member being employed for engaging said latch to maintain the latter in locking engagement with the said latch, a portion of one of the said flanges of the stiffening member being cut away to permit 65 said locking member to cooperate with the latch.

Other features of the invention residing 70 in advantageous forms and relations of parts will hereinafter appear and be particularly pointed out in the claims.

In the drawings showing a preferred form 75 of the invention,—

Figure 1 is a fragmentary elevational view looking toward the door of a railway car of the twin hopper type constructed in accordance with the invention.

Figure 2 is a fragmentary side elevational 80 view of the hopper, door and door locking mechanism illustrated in Fig. 1.

Figure 3 is a sectional view on the line 3—3, Fig. 2.

Figure 4 is a sectional view on the line 85 4—4, Fig. 1.

Figure 5 is a sectional view on the line 5—5, Fig. 1.

In the drawings 1 indicates the side of the car or the end sheet of the hopper, and 90 2 indicates the door by which the lading discharge opening of the hopper is closed. As is well known, the doors of cars of this type are hinged to the car body just above the door opening through which the lading 95 is discharged, such discharge opening being in an inclined plane substantially normal to the sloping bottom 3 of the hopper. The edges of the hopper sheets defining the discharge opening may be flanged, as indicated 100 at 4, to provide a seat against which the door 2 may close. The swinging door may also be formed with the customary marginal flange 5 for stiffening the door.

Motinted upon the outer face of the door 105 is a stiffening member 6. Where the doors are arranged in pairs on opposite sides of the car the door stiffener 6 serves to connect them so that they operate together in the well known way. The stiffening member is 110

of channel form and comprises spaced main flanges 7 which are integrally connected by a web 8, the main flanges being re-flanged at their free edges with marginal flanges 9 extending outwardly in opposite directions from said main flanges. These marginal flanges abut the outer face of the door 2 and extending through them and through said door are rivets 10 rigidly securing the door stiffener in position.

Pivotedly mounted between the door 2 and the web 8 of the door stiffener and extending between the spaced main flanges 7 of the latter is a latch 11 which extends outwardly beyond the adjacent side of the car for the purpose of cooperating with a shouldered member 12 to support the door in closed position. The door supporting member 12 is preferably in the form of a bracket rigidly secured to the sheet 1 of the hopper by means of the rivets 13 and provided with a notch affording ledges or shoulders 14 and 15, respectively, adapted to be engaged by said latch 11. The ledges 14 and 15 are in different planes and are spaced from each other in the direction in which the door swings, so that when the latch 11 cooperates with the upper ledge 14 the door will be retained in a partially closed position and when said latch engages the lower ledge or shoulder 15 the door will be retained in its position of final closure. It will be observed that the latch 11 and cooperating ledges 14 and 15 are so coordinated that the door may be brought to fully closed position without manipulating the latch to withdraw it from locking relation with the preliminary supporting shoulder 15. If desired the outer or free end of the latch 11 may be formed with a bent end or projection 16 serving not only as an operating means therefor, but also as a guide or stop for preventing slippage of a removable door closing lever or prying bar 17, as will hereinafter appear. The bent end 16 of the pivoted latch is, as shown, spaced away from the outer face of the shouldered door supporting member 12 in overlapping relation to the latter so as to afford a recess 50 through which said removable lever may extend.

As well shown in Fig. 4, the inner end of the latch 11 is preferably formed with an integral boss or hub 18 through which and through the door 2 and door stiffener 6 a rivet 19 extends. The outer end of the boss 18 preferably bears directly against the web 8 of the door stiffener member and its inner end may advantageously bear directly against the door 2. By this means the latch is enabled efficiently to resist the bulging pressure to which it is subjected when the door is sustaining the load imposed by the material transported by the car, since the inner face of the web 8 of the door stiffener

forms an abutment for the pivoted end of the latch 11, the supporting ledge 15 of the door supporting member 12 forms an abutment for the free end of the latch and a marginal door flange 5 is adapted to engage and be supported by the said latch between the ends of the latter.

A rotatable cam or dog 20 carried by the door is preferably employed to prevent the accidental release of the latch 11. To permit the cam to engage the latch a portion of one of the main flanges 7 of the door stiffener is cut away, as indicated at 21, thus permitting said cam to enter the space between the door and the web 8 of the door stiffening member and also enabling the latch to swing to the required extent without necessitating the use of a door stiffener of comparatively great width. The locking cam 20, which may be of a form now well known, is preferably pivotally connected to the door by means of a rivet 22 the outer end of which may conveniently be supported by a bracket 23 attached to the outer face of the door stiffening member 6 by means of rivets 24. The latch 11 and its locking cam 20 are preferably of such dimensions and so related that the cam cannot be forced into locking relation with the latch until the door is in fully closed position. The ability to rotate the cam to locked position thus affords an indication to the trainman that the door has been brought to a position of final closure.

As is well known, the rough usage to which cars are subjected in service often results in distorting the doors so that it is difficult to bring them to fully closed position, although they may be readily swung to a position approaching that of final closure. When a door equipped with locking mechanism constructed in accordance with the invention is swung toward closed position the lower edge of the latch 11 engages the inclined face or approach plane 24' at the outer end of the door supporting member 12 carried by the car body and the latch swings upwardly and then falls to a position where it cooperates with the preliminary ledge 14 so as to maintain the door in nearly closed position. When the door is thus temporarily supported a lever or prying bar 17 may be inserted between the member 12 and the bent outer end 16 of the door latch 11, the lower end of said lever being caused to abut against one of the railways ties 25 or other convenient fulcrum. By pressing against the upper end of the lever 17 when the latter is thus positioned the trainman is enabled to apply great force to the door and thus easily bring it to fully closed position. When the door is completely closed the pivoted latch 11 is moved into engagement with the final locking shoulder 15 of the door supporting member carried by the

car and the cam 20 is forced into locking engagement with the upper side of said latch.

I claim:—

- 5 1. A railway car having a hinged door, a stiffening member mounted upon the outer face of said door, said stiffening member being provided with a channel which opens toward said door, a latch pivotally mounted within said channel and extending outwardly beyond the end of said stiffening member, and means carried by the car body constituting a ledge adjacent said stiffening member adapted to cooperate with said latch to hold said door shut.
- 10 2. A railway car having a door, a stiffening member mounted upon the outer face of said door, said stiffening member being of channel form and comprising spaced main flanges connected by a web and provided at their free edges with marginal flanges, said marginal flanges being disposed between said web and said door, means extending through said marginal flanges for securing said stiffening member to said door, a shouldered member carried by the car body adjacent the end of said stiffening member, and a pivoted latch disposed between said main flanges of the stiffening member and adapted to engage said shouldered member to hold the door shut.
- 15 3. A railway car having a door, a stiffening member mounted upon the outer face of said door, said stiffening member being of channel form and comprising spaced main flanges connected by a web and provided at their free edges with outwardly extending marginal flanges, said main flanges being disposed substantially normal to the plane of said door, said web being spaced from and disposed substantially parallel to the outer face of said door, means extending through said marginal flanges for securing said stiffening member to said door, a pivoted latch extending between said main flanges of the stiffening member, and means carried by the car body constituting a ledge adapted to be engaged by said latch to hold said door shut.
- 20 4. A railway car having a door, a stiffening member mounted upon the outer face of said door, said stiffening member being of channel form and having spaced main flanges connected by a web and provided at

their outer free edges with oppositely extending marginal flanges, means extending through said marginal flanges for securing said stiffening member to said door, a latch pivotally between said main flanges of the stiffening member, and means carried by the car body adjacent the end of the said stiffening member constituting a ledge adapted to be engaged by said latch to hold the door shut, a portion of one of said main flanges being cut away adjacent said latch to afford clearance permitting an extended swinging movement of said latch.

5 5. A railway car having a door, a stiffening member mounted upon the outer face of said door and provided with spaced flanges disposed substantially normal to the plane of said door and connected by a web spaced from said door, a pivoted latch extending between said flanges, means carried by the car body adjacent the end of said stiffening member constituting a ledge adapted to be engaged by said latch to hold the door shut, and a locking member adapted to engage said latch to maintain the latter in engagement with said latch, a portion of one of said flanges being cut away to permit said locking member to engage said latch.

6 6. A railway car having a door, a stiffening member mounted upon the outer face of said door, said stiffening member being of channel form and including spaced flanges connected by a web which is spaced from the outer face of said door and disposed substantially parallel thereto, a latch pivotally mounted between said door and said web of the stiffening member and constituting a beam for resisting an opening movement of said door, and means carried by the car body adjacent the end of said stiffening member constituting a ledge adapted to be engaged by said latch to hold the door shut, said door having a marginal flange adjacent said latch, the inner face of said web of the stiffening member forming an abutment for the pivoted end of said latch, the said ledge forming an abutment for the free end of said latch, and the said door flange being adapted to be supported by said latch between the ends of the latter.

In testimony whereof I affix my signature.
